ROLLER DRIVE DISENGAGING MEANS FOR
POWER-DRIVEN WRINGERS

Robert D. O'Callaghan, Des Moines, Iowa

Application March 7, 1938, Serial No. 194,407

4 Claims. (CL. 68—249)

The principal object of this invention is to provide a disengaging means for roller actuated washing machine wringers which positively disengages the power roller of the wringer from the 5 driving means when the wringer is opened by the release of the ordinary safety catch.

A further object of this invention is to provide a disengaging means for roller actuated washing machine wringers particularly adapted to roller 10 type wringers of the end opening type which will cause the driven roller to be disengaged from the driving means to provide greater safety to the operator of the wringer.

A still further object of my invention is to provide 15 a disengaging means for roller actuated washing machine wringers that is used directly adjacent the end of the driven roller, making the complete wringer and safety attachments a self-contained unit having all of its actuating and 20 operating parts ahead of the drive shaft or power transmission means to the wringer roll.

A still further object of this invention is to provide a disengaging means for roller actuated washing machine wringers that is positive in its 25 action.

A still further object of this invention is to provide a disengaging means for roller actuated washing machine wringers having in conjunction therewith, a frictional wringer drain operating 30 mechanism.

A still further object of this invention is to provide a disengaging means for roller actuated washing machine wringers that is economical in manufacture, durable and efficient in use.

35 These and other objects will be apparent to those skilled in the art.

My invention consists in the construction, arrangement, and combination of the various parts of the device, whereby the objects contemplated 40 are attained as hereinafter more fully set forth, pointed out in my claims, and illustrated in the accompanying drawing, in which:

Fig. 1 is a side cross-sectional view of a portion of a wringer with my device installed thereon 45 ready for use.

Fig. 2 is an end sectional view of the shaft and disengaging rack taken on the line 2—2 of Fig. 1.

Fig. 3 is a cross-sectional view of my device taken on the line 3—3 of Fig. 1.

50 Fig. 4 is a side elevational view of the engaging fork used in my disengaging means for roller actuated washing machine wringers.

Heretofore, roller actuated washing machine wringers have had several serious drawbacks. 55 The chief objections to wringers of this type have

been the difficulty of providing adequate safety devices to prevent injury to the operator of the roller. The end operated or vertically swung, type of wringer has been desired by virtue of the fact that it could easily be equipped with safety 5 catches for disengaging one roller from the other and preventing injury to the operator through crushing of a hand or arm between the rollers. This has been accomplished satisfactorily, but due to the fact that the lower roller continues to 10 rotate, additional hazards are incurred, as the hand or arm of the operator may become entangled in the clothing being passed through the wringer and the movement of the roll tends to 15 pull the arm into the mechanism. No satisfactory method has heretofore been devised for positively disengaging the lower roller from the driving mechanism when the upper roll has been 20 disengaged through use of safety catches and the like from the lower roller.

I have overcome such disadvantages by providing a disengaging means for roller actuated washing machine wringers that positively disengages the lower roll of the wringer from the driving 25 means when the upper roll is disengaged by the safety release ordinarily provided on the wringer.

Referring to the drawing, I have used the numeral 10 to designate the lower frame of an ordinary wringer. The numeral 11 designates 30 the upper roll of an ordinary wringer, ordinarily pivoted at one end to the frame 10 and yieldingly held adjacent the frame 10 in the usual manner. The numeral 12 designates the upper roll of the wringer rotatably mounted in the upper frame 11 35 as shown in Fig. 1 of the drawing. I have used the numeral 13 to designate a drive shaft rotatably mounted in the frame 10 which ordinarily has one end in operative engagement with a prime mover, transmission or the like. The 40 shaft 13 is embraced by the ordinary bearing cap 14, which in turn has an enlarged chamber 15 45 therein as shown. I have used the numeral 16 to designate a hexagonal portion integrally formed on the shaft 13 within the chamber 15 in prolongation of the shaft 13, which serves as a driving spindle for my device at times.

The numeral 17 designates a pin shaft integrally formed on the inner end of the hexagonal portion 50 16. I have used the numeral 18 to designate the lower roller of the wringer rotatably mounted in the frame 10 and having a hollow shaft 19 at one of its ends. The portion of the shaft 19 extending beyond the end of the wringer has cut therein, a hexagonal opening into which 55

operatively embraces my safety means which I will now describe.

The clutch portion of my device is formed from a single piece of material having a bore 5 through its longitudinal center line, capable of slidably engaging the pin 17. The numeral 20 designates a hexagonal portion at the inner end of my device for slidably engaging the hexagonal opening in the shaft 19 for preventing independent 10 rotation between the shaft and my device relative to each other. The numeral 21 designates a groove cut in the sleeve of my device and about its peripheral edge, as shown in Fig. 1. The outer end of this sleeve has cut therein, 15 parallel with its longitudinal center, a hexagonal opening 22, capable of receiving the hexagonal member 16, when the sleeve is in the position shown by dotted lines in Fig. 1. I have used the numeral 23 to designate a yoke member having 20 one end pivotally secured to the frame 10 below the longitudinal center of the lower roller driving mechanism and having a circular lug 24 formed on its upper end. I have used the numerals 25 and 26 to designate lugs rigidly secured to the 25 inner sides of the yoke 23 for engaging the slot or groove 21 of my operating mechanism as shown in Fig. 2 of the drawing. The numeral 27 designates a coil spring imposed between the yoke 23 and the inside wall of the frame 10 for yieldingly 30 holding or retaining the yoke in position. The numeral 28 designates an engaging fork having its upper end secured to the frame 11 of the upper roller 12, and so designed that when the upper frame 11 is closed so that the rollers 12 and 18 35 are adjacent each other, the fork 28 will engage the lug 24, pulling the yoke to the position shown by dotted lines in Fig. 1 and placing the hexagonal hollow portion 22 in operative engagement with the hexagonal portion 16 for driving the roller 40 18.

Ordinarily, there is a tilttable drain board below the lower roll of all roller type wringers, generally actuated by a friction portion bearing directly on the rubber part of the roll. I have provided a tilttable drain board 29 pivotally mounted on the frame 10 below and adjacent the roll 13 and having a crankarm 30 on one end thereof. The numerals 31 and 32 designate friction fingers frictionally engaging or embracing the outer peripheral edge of my clutch portion and retained in position by a clip spring 33 as shown in Fig. 3 of the drawing. The portions 31 and 32 have elongated fingers extending downwardly and at an angle thereto which I have designated by the numerals 34 and 35 respectively for contacting and actuating the crankarm 30 at times. I have used the numeral 36 to designate my sleeve bearing in the shaft 19 in its entirety for aiding in the explanation of the practical operation of my device, which is as follows: When the wringer is in operation, the rolls 12 and 18 are adjacent each other as shown by dotted lines in Fig. 1, and the fork 28 is holding the sleeve 36 so that the hexagonal opening 22 embraces the hexagonal portion 16, engaging the sleeve 36 with the shaft 13. Power from the shaft 13 is transmitted to the sleeve 36 by virtue of the opening 22 being in engagement with the hexagonal portion 16. The hexagonal portion 20 is in engagement with the hexagonal opening in the shaft 19, thereby providing power for the rotation of the roll 18. Should something occur that makes it necessary to release a safety catch and open the rollers relative to each other, the fork 28 will carry the lug 24 and yoke 23 inwardly until the lug 24 is

released by the fork 28, thereby pulling the opening 22 out of engagement with the hexagonal portion 16 and preventing power from being transmitted to the roller 18, thus preventing accidents from occurring, due to the rotation of this roller. When the housing or upper frame 11 is again closed, the longer inside finger of the fork 28 picks up the lug 24, moving the yoke 23 to the position shown by dotted lines in Fig. 1, bringing the opening 22 over and in engagement with the hexagonal portion 16 and again allowing the shaft 13 to directly power the roll 18 through the medium of the sleeve 36. The spring 28 is of sufficient tension to hold the yoke 23 in position to prevent accidental engagement of the sleeve 36 with the hexagonal portion 16. The frictional portion of my device or drain tilting means frictionally embraces the sleeve 36 with sufficient traction to pull the fingers 34 or 35 into engagement with the crankarm 30 for tilting the drain 29 to its proper attitude relative to the rotation of the roll 18.

Thus it will be seen that I have provided a disengaging means for roller actuated washing machine wringers that is positive in operation and simple in construction and which fulfills all of my objects. Furthermore, my complete safety device is positioned adjacent the roll of the device and ahead of the transmission or powering means. Also, the friction member for engaging the wringer drain board is adjacent the clutch portion and is in frictional contact with the metallic sleeve 36, eliminating undue damage to the rubber roller and applying an actuating pressure on the crankarm for tilting the drain portion without impairing the efficiency or operation of the wringer roll.

Some changes may be made in the construction and arrangement of my improved disengaging means for roller actuated washing machine wringers without departing from the real spirit and purpose of my invention, and it is my intention to cover by my claims any modified forms of structure or use of mechanical equivalents which may be reasonably included within their scope. 40 45

I claim:

1. In combination with a washing machine wringer having a lower frame, a drive shaft rotatably mounted in the lower frame, an upper frame hingedly secured at one of its ends to the lower frame and having a roller rotatably mounted therein, a lower roller rotatably mounted in said lower frame, a hollow shaft portion on said lower roller extending beyond its end portion, a hexagonal opening in the end of said hollow shaft, a hollow sleeve portion having one of its ends hexagonally shaped and capable of sliding engagement with said hexagonal opening in said hollow shaft, a hexagonal portion on the inner end of said drive shaft, a pin shaft on the inner end of said hexagonal portion capable of engagement with the inside opening in said hollow sleeve, a hexagonal opening in the outer end of said sleeve capable of engagement with said hexagonal portion of said shaft at times, a slot cut about the peripheral edge of said sleeve, a yoke element having its lower end pivotally secured to said frame, lugs on said yoke element capable of operative engagement with said groove in said sleeve, a circular lug formed on upper end of said yoke, and a fork member rigidly secured to said upper frame; said fork member being capable of engaging said circular lug said yoke when said upper frame is pivoted.

causing said lugs on said yoke to actuate said sleeve causing said hexagonal opening in said sleeve to engage said hexagonal portion on said drive shaft.

5. 2. In a device of the class described, a lower frame portion, an upper frame portion hingedly secured at one of its ends to the lower frame portion, a lower roller rotatably mounted in said lower frame portion, an upper roller rotatably mounted in said upper frame portion, a drive shaft, a clutch means capable of operatively connecting said drive shaft to said lower roller, and a rigid member on said upper frame portion capable of operatively engaging said clutch 10 means for operatively disengaging said drive shaft from said lower roller when said upper frame portion is moved upwardly and away from said lower frame portion.

15. 3. In a device of the class described, upper and lower frame portions, a horizontally dis-

posed roller rotatably mounted in each frame portion, a hinge connecting said frames together at one end, said hinge permitting said upper frame to swing into and out of abutting relation to said lower frame through a vertical arc 5 in alignment with the axes of said rollers, a drive shaft, a clutch for connecting said drive shaft to said lower roller, means inwardly of said lower frame and adjacent said hinge for automatically disengaging said clutch when said upper frame and roller are swung upwardly on said hinge, and means automatically re-engaging said clutch when said upper roller and frame are swung downwardly to abut said lower frame and roller. 10

15. 4. The structure of claim 3, said clutch disengaging means comprising a spring carried by said lower frame and operatively connected to said clutch to load the same towards a disengaging position.

ROBERT D. O'CALLAGHAN. 20
